(57) **CLAIM**

The ornamental design for a pad for electronic hi-hat, as shown and described.

DESCRIPTION

FIG. 1 is a first perspective view of a pad for electronic hi-hat showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a third perspective view thereof, showing that the pad for electronic hi-hat in close and flat state is attached to a hi-hat clutch;

FIG. 10 is a fourth perspective view thereof, showing that the pad for electronic hi-hat in open and flat state is attached to a hi-hat clutch; and,

FIG. 11 is a fifth perspective view thereof, showing that the pad for electronic hi-hat in open and oblique state is attached to a hi-hat clutch.

The broken lines in the drawings depict portions of the pad for electronic hi-hat that form no part of the claimed design.
